PLATEN MOUNTED ELECTRIC SWITCH

Filed Nov. 28, 1924

UNITED STATES PATENT OFFICE

WILLIAM S. EDSALL, OF BOSTON, MASSACHUSETTS, ASSIGNOR, BY MESNE ASSIGNMENTS,
TO CONDIT ELECTRICAL MANUFACTURING CORPORATION, OF BOSTON, MASSA-
CHUSETTS, A CORPORATION OF MASSACHUSETTS

PLATEN-MOUNTED ELECTRIC SWITCH

Application filed November 28, 1924. Serial No. 752,730.

This invention relates to electric switches and has particular reference to the so-called platen-mounted type of electric switch.

It is now common practice to mount oil-immersed electric switches on elevated platens or shelves in such a manner that the upper portion of the switch casing rests upon the platen while the lower portion, or removable oil receptacle, depends below the platen and can be lowered and removed without disturbing the connections between the switch terminals and line conductors. This arrangement is desirable, for one reason, in that the alignment between the switch terminals and the fixed line terminals can be accurately predetermined and preserved.

The platen is usually provided with a slot extended inwardly from the forward edge thereof, in which the switch is disposed; and the switch has supporting members which project laterally beyond the boundaries and seat upon the platen.

In mounting the switch upon the platen the switch is usually elevated, in a suitable manner, in front of the platen, to such a height that its supporting members are slightly above the platen, and is then pushed rearwardly, in frictional engagement with the platform, to its proper position thereon. The switch usually is relatively heavy and consequently the work of sliding the switch along the platform is considerable.

It is an object of this invention to provide a switch adapted for platen mounting with wheeled means adapted to bear upon the platen and by which the switch may be moved easily upon the platen into and from its service position thereon.

It is a further object of this invention to arrange said wheeled means so that they may be removed from supporting engagement with the platen and permit the supporting members to rest directly upon the platen with the switch terminals in connection with the line conductors.

A platen-mounted electric switch is or may be provided with means for connecting and disconnecting it automatically with the fixed circuit terminals during the movement of the switch into and from service position. Such

automatic disconnecting switches are more or less troublesome in that the contact pressure between the current-carrying components of the switch is sometimes insufficient to withstand the magnetic forces tending to separate such components due to a heavy current traversing them.

It is a further object of this invention to provide an improved form of disconnecting switch wherein the relatively separable current-carrying components thereof are urged into contact with a substantial amount of pressure and, specifically, with a substantial proportion of the total weight of the oil switch.

A yet further object is the provision of means whereby the act of raising the switch above the platen, to support the switch upon its wheeled structure, automatically opens the disconnecting switch.

A yet further object is generally to improve the construction and operation of electric switches and associated apparatus.

Fig. 1 is a side elevation of an electric switch and its platen mounting and illustrating the invention.

Fig. 2 is a rear elevation of the upper portion of the switch of Fig. 1.

Fig. 3 is a detail of one of the supporting wheels disposed in switch-supporting position.

Fig. 4 is a sectional detail of a contact brush of the disconnecting switch.

As here shown the platen-mounting for the switch includes a platen 10 which is usually disposed in elevated position above the floor of the switch room and may be contained in an enclosing cell, as shown. Said platen is formed with a slot 12 which is extended inwardly from the forward edge 14 thereof; and the switch is adapted to be received in and to project both above and below the platen. The stationary elements of the disconnecting switches, one being shown in Fig. 1, are mounted on the platen in the rear of said slot 12, and each may comprise an insulator 15 fixed to the platen, and a contact block 16 fixed to the upper end of the insulator and adapted for connection with a line conductor. Said contact block may be formed with a

100

recess 18 in its upper face which may contain an insulating medium, as oil, whereby to cover the contact faces of both said block and the movable contact member carried by the switch, and prevent oxidation thereof.

5 The main electric switch may include a casing comprising the switch frame 20 and the oil receptacle 22 which depends below the switch frame. The oil receptacle may be 10 yieldingly connected with the switch frame and, to this end, may rest upon the carriage 24. Rods 26 may be connected with said carriage and extend upwardly about the oil receptacle and pass freely through laterally- 15 extended lugs 28 of the switch frames. Helical springs 30 may loosely surround the upper ends of said rods, above said lugs, and nuts 32 may be adjustably screw-threaded on said rods and arranged to bear upon the upper ends of said springs.

20 The carriage 24 may be provided with wheels 34 by which the switch may be transported readily about on the floor of the switch room.

25 The switch is provided with switch terminals 36 which are carried by the switch frame and extended upwardly thereabove.

The electric switch is adapted to be supported from the platen by a supporting frame, 30 which frame is also adapted to support the movable members of the disconnecting switch.

Said supporting frame includes the base members 38 which are disposed on opposite sides of the switch casing, beneath the lugs 35 28, and are fixed to said lugs by suitable means as the bolts 40. Said base members are adapted to rest upon the platen on opposite sides of the slot 12 therein and to provide support for the switch. Spaced up-

40 rights 42 are secured to the rear ends of said base members and a cross-plate 44 connects the upper ends of said uprights and provides support for insulating bushings 46. Said bushings are disposed approximately horizontally in line with the upper ends of the switch terminals and conducting rods 48 are extended through said bushings and are provided with detachable electric connections with said switch terminals at their forward ends.

Said supporting frame is also provided with a horizontal shelf including members 50 which are fixed to said uprights 42 intermediate the ends thereof, and are extended 55 horizontally rearwardly therefrom. A plate 52 is extended between and fixed to said horizontal members 50 and, bushings 54 are secured vertically in said plate. Conducting rods 56 are extended through said bushings

60 and the upper ends thereof are detachably connected electrically with said rods 48 at their rear ends. Blocks 58 are carried by the lower ends of said rods 56 and one or more pairs of divergent brush members 60 may be carried by each block. Said bushings 54

and brush members are disposed for vertical alignment with the fixed contact members 16 of the disconnecting switch and the brush members are adapted for detachable engagement with said blocks in the manner illustrated in Fig. 1.

Wheeled means are provided for supporting the switch upon the platen as it is moved therealong into and out of service position. Said means includes hand-operated levers 62 which are disposed adjacent the corners of the supporting frame and are pivoted thereto by pins 64. Rollers 66 are journalled on the lower ends of said levers. When the switch is in the service position on the platen as illustrated in Fig. 1, said levers and rollers are moved away from supporting relation between the switch and platen, as shown, and the supporting frame rests directly upon the platen. When, however, the switch is to be withdrawn from its normal position, said levers are adapted to be moved about their pivots, toward the right, Fig. 1, and into a position illustrated in Fig. 3, whereby to raise the switch and its supporting frame above the platen and dispose the rollers 66 in contact with the platen and in switch-supporting position. In this position the switch may be readily withdrawn and the switch will roll over the platen on said rollers.

Suitable means may be provided to hold the levers 62 releasably in switch-supporting relation. Said means may include latches 68 which latches may be pivotally connected with said levers 62 above the pivots 64 and arranged to engage with fixed pins 70 carried by the supporting frame. The switch may be lowered onto the platen by first releasing said latches.

The act of raising the switch above the platen by operating the roller-levers 62 also serves to raise the brush members 60 of the disconnecting switch away from engagement with the fixed contact-members 16 thereof, thereby opening the disconnecting switch. The dimensions and relation of the various parts of the disconnecting switch are adapted to be such that, when the main switch is in service position, a substantial portion of its weight is borne by the brush members of the disconnecting switch, thereby ensuring a firm contact at the disconnecting switch, although the arrangement is such that, preferably, the main switch is yet securely seated on the platen.

The structure may be otherwise modified without departing from the spirit of the invention.

I claim:

1. An electric switch including a casing having supporting wheels on the bottom thereof by which the switch can be moved about on a floor, a switch-supporting frame surrounding said casing intermediate its ends, means connecting said frame and casing, and

- frame-supporting rollers carried by said frame.
2. A truck-type electric switch including a casing having supporting wheels on the bottom thereof by which the switch can be moved about on a floor, means including rollers carried externally by said casing intermediate the ends thereof arranged to support the switch for horizontal movement upon an elevated support.
3. An electric switch including a casing having supporting members intermediate the ends thereof, switch supporting rollers, and means to move said rollers into and out of position beneath said supporting members.
4. An electric switch including a casing having supporting members intermediate the ends thereof, switch-supporting rollers, and means to move said rollers into and out of position beneath said supporting members including levers pivoted to said casing and having supporting means for said rollers below said pivotal connections.
5. An electric switch including a casing having supporting members intermediate the ends thereof, switch-supporting rollers, and means to move said rollers into and out of position beneath said supporting members including levers pivoted to said casing and having supporting means for said rollers below said pivotal connections and means to hold said levers releasably in switch-supporting relation.
6. An electric switch including a casing having supporting members intermediate the ends thereof, switch-supporting rollers, means to move said rollers into and out of position beneath said supporting members including levers pivoted to said casing and having supporting means for said rollers below said pivotal connections and means to hold said levers releasably in switch-supporting relation including latches carried by said levers, and cooperating locking-projections carried by said casing.
7. An electric switch including a casing having truck wheels at its lower end to support it for movement on a floor, a supporting frame for said casing disposed about and secured to said casing intermediate the ends thereof, and rollers carried by said frame intermediate the ends of said casing.
8. An electric switch including a casing, a supporting frame disposed about and secured to said casing intermediate the ends thereof, and rollers carried by said frame having means to move them into and out of switch-supporting position below said supporting frame.
9. The combination of an electric switch including a casing, a supporting frame secured to said casing intermediate its ends, and an enclosing fixed support adapted to engage said frame and support the casing, and means carried by the supporting frame arranged to elevate the casing bodily above said support.
10. The combination of an electric switch including a casing, and a fixed support adapted to engage and support the casing intermediate the ends thereof, and means carried by the casing and having provision for movement into and out of effective engagement with said support arranged to elevate the casing bodily above said support.
11. An electric switch including a casing, switch terminals carried thereby, a supporting frame disposed about and carried by said casing intermediate the ends thereof, a disconnecting switch having its movable member carried by said frame and connected electrically with one of said switch terminals, and rollers carried by said frame having means to move them into and out of switch-supporting position beneath said frame.
12. The combination of a main switch, a disconnecting switch therefor having separable contact members that abut across the line of separation of said contact members, and means permitting the weight of said main switch to exert a pressure on said contact members, whereby to hold said disconnecting switch closed.
13. The combination of fixed line terminals, a circuit interrupter having supporting wheels on which the interrupter is movable horizontally with respect to said line terminals and having means for moving said wheels toward and away from each other to move the interrupter vertically above and relative to said wheels, and switch terminals carried by the interrupter movable vertically therewith by the operation of the aforesaid means into and out of engagement with said fixed line terminals.
14. The combination of fixed line terminals, a circuit interrupter having interrupter terminals adapted to cooperate with said fixed line terminals, a support on which said interrupter is movable horizontally, said interrupter having supporting wheels which roll upon said support and provide for horizontal movements of the interrupter, and means carried by said interrupter to raise and lower it relative to said support to effect engagement and disengagement of said interrupter and line terminals including means to move said wheels along said support relatively both to said support and to said interrupter.
- In testimony whereof, I have signed my name to this specification.
- WILLIAM S. EDSALL.
